UNITED STATES PATENT OFFICE.

CHARLES VICTOR THIERRY AND MICHEL THIERRY, OF PARIS, FRANCE.

ELECTRIC ZINC-FURNACE WITH INTEGRAL CONDENSER.

1,122,663.

Specification of Letters Patent.

Patented Dec. 29, 1914.

Application filed May 21, 1913. Serial No. 768,991.

To all whom it may concern:

Be it known that we, CHARLES VICTOR THIERRY and MICHEL THIERRY, both citizens of the Republic of France, and residents of the city of Paris, in said Republic of France, have invented certain new and useful Improvements in Electric Zinc-Furnaces with Integral Condensers, (Case A,) of which the following is a specification.

This invention relates to the metallurgy of zinc, having for its object the production of zinc-fume and its subsequent condensation to liquid metal. The particular means for attaining the desired results and such an elucidation of the general principles involved as may appear necessary will be currently described and pointed out in connection with the accompanying drawings; which denote an embodiment of the invention.

Figure 1 is an end elevation; Fig. 2 is a transverse section, as on the line A of Fig. 3; Fig. 3 is a longitudinal center section, as B, Fig. 2, from left hand end of the furnace to the center line K, while the right hand side of the figure is taken along either of the lines C, or C¹, from above and thence down to the points D, or D¹, and Fig. 4 is a top plan view from the left hand side of the center line, K, while the right hand portion of the illustration is a horizontal section along the planes H and J, of Fig. 2.

This furnace is particularly intended for the reduction of oxid of zinc such as commercial oxid of zinc combined with carbon in the form of coke, coal or the like as the reagent whereby, when adequately heated, substantially the following representative reaction ensues, namely:

40

If pure ZnO and C are used in precisely correct relative proportions then the answer of the above formula is an exact expression of the result in that all of the charged material would be volatilized as zinc fume and monoxid of carbon in which case there would be no residue. Such conditions, however, do not obtain in commercial practice as more or less inert residual matter will remain, depending upon the purity of the materials employed and hence the formula becomes simply representative as above stated.

The presence of this residual matter is a cause of difficulty in realizing a successful result.

The heat necessary for decomposing the charge is preferably derived by direct conduction or by radiation or by both, from a "resistor" X formed of a bed of broken carbon, interpolated between terminals as 5, 5^a, suitably connected to a source of electric energy, indicated by the power circuit, P.

In cross section, the resistor is relatively thin, with respect to its breadth, and is supported along its lower narrow edge in a sump, 6. The vertical longitudinal sides of the resistor are preferably confined by right and left hand spaced plates, as 7, set on edge vertically and disposed transversely to the resistor. Thus there are provided by and between said plates chutes or pockets, as M, whose bottoms, 8, may be sloped downwardly toward the trough.

Above the resistor is a longitudinal chamber Y, wider than the resistor, having two right and left hand troughs, 9, 9^a. This longitudinal chamber is divided into transverse sub-chambers as N, Fig. 3, by bricks or tiles, 12, as 12. The sub-chambers, and the spaces between the troughs, are preferably filled with broken carbon; which rests upon the upper edge of the resistor and upon the troughs. The tiles, 12, serve as thrust-members and also to prevent a direct flow of electricity through the carbon in the sub-chambers; hence this carbon is heated by conduction of heat from the upper edge of the resistor and its hottest zone is immediately above the resistor.

That portion of the furnace immediately above the lower edges, as, 13 of the tiles constitutes a portion of the condenser, and for convenience of description may be designated as the filtering section, or the filter.

From an inspection of Fig. 2 it will be observed that the combined furnace and condenser comprise a central T-shaped portion having at the bottom of the T a broken carbon resistor and at the upper part of the T broken carbon into which the product from the resistor passes and from which any fumes, not condensed therein, and gases pass to the condensing fissures located above the broken carbon. It will furthermore be noted that the troughs or receptacles 9—9^a are located under the carbon in the arm of the T-

shaped portion and also that said troughs are located above the zone in which the reaction takes place in the furnace.

The filter is inclosed by a series of covers, 5 V, constructed of refractory material in which are formed a plurality of vertical fissures, slits, slots or perforal openings as h, which pass entirely through the said covers. These fissures are preferably disposed in two 10 series, as see Figs. 2 and 4, each set being divided from the other by a solid center portion, as 14. Thus each series of these slots are directly above one or the other of the troughs, 9, 9^a. Then, too, on top of the 15 covers are laid flanged pans, as 15, which in cross section, Fig. 2, are like the letter I, thereby forming a pan like receptacle above and a space or chamber, as w, beneath. In these pans are adjusting screws, 15^a, located 20 off-center, whose points impinge upon portions of the cover, as shown.

Arranged along the outer longitudinal walls of the furnace are a number of vertical tubes, as 16, 16^a, open at both ends, and coinciding with the pockets, M, but beneath 25 said tubes are transverse stoke openings, 17, 17^a, in the side walls, which connect with the chutes.

The operation of the furnace is as follows: 30 Composite charge-material (ZnO+C) is fed into the tops of the tubes, as L, Figs. 2 and 4, thence gravitating down and into the pockets and flowing inwardly until arrested by the vertical faces of the resistor. 35 Should the pockets not pack sufficiently full, this can be effected by poking through the stroke-openings in the side walls. When reaction is established along or contiguous to the upright faces of the resistor, that is 40 those portions thereof exposed to the charge between the files which form the pockets, the volatilized products, Zn and CO, flow horizontally in to the interstices of the resistor, thence vertically upwardly through 45 the filter and are deflected right and left, by the center portion 14, to the outside portions of the filter-carbon and thence on to the condensing fissures in the covers, as indicated by the arrows c. Fume condensed 50 to liquid metal, in the form of globules, will then gravitate, as arrows d, down through the filter-carbon and be collected in the underlying troughs, or receptacles, from whence it may be tapped off, as at i, Fig. 3. 55 Among the conditions essential to effective condensation of zinc-fume it is important that there shall be a progressive diminution in temperature from or near the seat of reaction to the location of final precipitation as a liquid. This feature is realized 60 by the radiation of heat to atmosphere of the slotted covers, and the rate thereof is a function controllable by the pans; which are preferably formed of sheet or cast metal. 65 Now, by more or less filling the pans, as

with sand, oxid, ground carbon, or mineral wool, the rapidity with which the heat-units will escape can be determined to suit the requirements. These pans are also utilized for controlling the rate of escape of CO, the 70 screws being turned in or out to tilt the pans and permit the flow of gas to atmosphere, as denoted in Fig. 2. Non-volatilized matter, that is inert residual dust, ash or sinter, gravitates downwardly toward the 75 lower edge of the resistor, to percolate or be poked into the sump from whence it may be intermittently scraped out through suitable end-openings, not shown.

It may be pointed out that the tiles or 80 bricks which form the pockets serve the important function of preventing a direct traverse of electric current through the charge, when the latter is in physical contact with the resistor, and they also provide 85 free zones in the resistor for the dispersion and flow, at a reduced velocity, of the fume and gas.

The covers are readily removable for inspection of the filter or its renewal, and this 90 may also be done in the case of the resistor.

The slits or fissures are preferably of wedge-section, widest at the bottom, which are the most convenient to mold and also to clean out if clogged, but the cross-sectional 95 dimensions or form thereof are in no wise limited to that shown in the drawings.

In a sense, the pans perform the function of the "balloons" in the old method of zinc smelting; for if fume fails to condense as a 100 liquid in its transit through the filter and the fissures, it will or may be congealed as "blue-powder" in the pan-chambers, collecting upon the upper faces of the material between the condensing slots. On the other 105 hand, if the rate of evolution of fume and gas is very rapid, and the condensation is quite completely effected in the filters and cover-slots, then the pans may be dispensed with and the issuing CO may mingle directly with atmosphere or be burned to CO₂. 110

The thermal advantages of "blanketing" the high temperature portions of the furnace with charge-material and of causing the reaction to proceed along the vertical faces of a resistor have been elsewhere pointed out at length and need not be here repeated; and the same observation applies broadly to a condensation system comprised in fissured or perforated chamber walls. But the organization and construction of these features, as here presented, are novel, practical and of use in the art, yet various modifications may be made in the detail hereof without departing from the spirit and essence of 115 the invention.

We claim as our invention:

1. An electric zinc furnace having a resistor whose side surfaces are partially retained by spaced plates, a sump directly 120

beneath the resistor and by means of which the said resistor is sustained.

2. In an electric zinc furnace a bed of carbon resistor resting in or upon a sump, a series of inclosed charge-pockets disposed along the vertical side or sides of said resistor and a series of vertical tubes for supplying the said pockets with charge-material.

10 3. In an electric zinc furnace a bed of carbon resistor, a series of inclosed charge pockets disposed transversely to and along the side or sides of said resistor, a series of vertical tubes for supplying the said pockets with charge-material and stoking openings in the side-walls.

4. In an electric zinc furnace a bed of carbon resistor arranged and constructed to act upon charge-material disposed along its 20 vertical sides, the volatilized products of the reaction passing primarily into the resistor and thence vertically upward, liquated zinc being collected in right and left hand reservoirs located above the plane of said 25 resistor, while the uncondensed fume and gas flow upwardly and out to atmosphere.

5. In an electric zinc furnace a bed of carbon resistor and a series of superimposed filter chambers filled with carbon, the chambers being wider than the carbon resistor and the filter carbon being partially supported by the said resistor.

6. In an electric zinc furnace a bed of carbon resistor, a series of superimposed filter-chambers filled with carbon partially supported by said resistor and a trough or troughs, disposed in a plane above the said resistor, for collecting liquid zinc.

7. In an electric zinc furnace a bed of carbon resistor, a series of superimposed filter chambers and troughs for collecting liquid zinc, said chambers being filled with carbon partially supported by the resistor and partially by the troughs.

45 8. In an electric zinc furnace a bed of carbon resistor and superimposed filter chambers filled with carbon whose hottest zones are immediately above the resistor.

9. In an electric zinc furnace having a 50 filter chamber or chambers located above a

resistor adapted to receive the volatilized products of the reaction from below, a primary cover or covers therefor provided with a plurality of vertical slits, fissures or perforal openings, in which fume is condensed but through which any residual fume and gas escape to a supplemental chamber, or chambers, formed upon the top of the primary cover and thence directly to atmosphere.

10. In an electric zinc furnace, a cover or covers provided with a plurality of vertical slits, fissures, or perforal openings, in which fume is condensed and through which any residual fume and gas pass upwardly, entering from below, and a pan or pans, resting upon the said cover or covers, adapted to control the temperature of the issuing fume or gas.

11. An electric furnace having a resistor, 70 along the vertical sides of which the reaction takes place and located over the resistor a condensing system having therein broken carbon which contacts with the resistor and which is provided with a receiving trough 75 which is located above the reaction zone.

12. A combined zinc furnace and condenser having in the central portion thereof a T-shaped space filled with broken carbon and provided at the lower portion of the 80 T with a resistor, along the opposite sides of which the reaction takes place, the products of the reaction passing into the resistor, thence upwardly through the rest of the carbon in the T-shaped space.

13. In a combined zinc furnace and condenser a portion providing a T-shaped space filled with broken carbon having at the bottom of the T a carbon resistor and below the carbon in the arms of the T a trough or 90 receptacle for liquid zinc.

This specification signed and witnessed this 5th day of May A. D. 1913, in the city of Paris, in the Republic of France.
